UNITED STATES PATENT OFFICE.

ERNST EISEMANN, OF STUTTGART, GERMANY.

IGNITION-COIL.

1,108,892.

Specification of Letters Patent.

Patented Sept. 1, 1914.

Application filed November 9, 1911. Serial No. 659,409.

To all whom it may concern:

Be it known that I, ERNST EISEMANN, a subject of the German Emperor, and residing at Stuttgart, Germany, have invented 5 certain new and useful Improvements in Ignition-Coils, of which the following is a specification.

This invention relates to ignition coils for battery or double ignition.

10 Whether it is solely a matter of the ignition of an internal combustion motor by means of the same, or of an auxiliary ignition in the case of so-called double ignition, the disadvantages of battery ignition are 15 due, on the one hand, to the diminution of the strength of the spark as the speed of the motor increases, caused by the impedance of the coil, and, on the other hand, to the strength of the spark not being able to 20 be increased in any way by increasing the battery voltage, the platinum contacts of the trembler being thereby subjected to very rapid wear.

A primary object of my invention is to 25 obviate these defects.

The invention substantially consists in connecting in series with the primary winding of the coil a resistance which, when the speed of the motor is low and the successive 30 breaks follow one another correspondingly slowly, allows only a certain maximum current to flow through the primary winding in consequence of the ohmic resistance of the resistance and the fall in tension brought 35 about by it. When the speed rises, however, and the strength of current diminishes in consequence of the impedance of the resistance coil being increased owing to the rapid successions of breaks, the ohmic drop 40 also decreases in ratio so that the voltage available at the terminals of the primary winding is correspondingly greater.

By correctly proportioning the primary winding of the ignition coil and the resistance coil I can provide that the inductive 45 action of the ignition coil remains approximately constant at the lowest and highest speed, and consequently that the sparks remain nearly equally powerful independently 50 of the speed.

For a more detailed understanding of the invention, reference is to be had to the following description and appended claims taken in connection with the accompanying

drawings, in which the figure is a central 55 vertical section of the device with the wiring shown diagrammatically.

The apparatus is in the form of a unitary structure which can be mounted at any suitable point on the automobile or engine with 60 which it is to be used. The device comprises a casing *a* of insulating material which is provided with a metallic ring *d* on which is fastened a cap *c*. Within the casing *a* is a magnetic core *o* on which are primary 65 and secondary windings *A* and *C*, the first winding consisting of a few turns of coarse wire and the latter of many turns of fine wire. In the lower end of the casing is a disk or plate *5* of insulating material which 70 carries the binding posts *t* and *r*, the former of which forms a common terminal for the lower ends of both the primary and secondary windings, while the latter forms the terminal for the upper end of the secondary 75 winding.

The core *4* has its lower end fitted in a metallic cup *8* which is partially countersunk or set into the disk *5* and is held in place by a bolt *u* which is screwed into the 80 cup, and its upper end fits into a cup *m* on the lower face of the plate *n*. The said bolt is anchored or otherwise fastened in the disk *5* and extends centrally through the spool-like core or support *10* formed on the bottom of the lower cap *11* for the casing *a*, which cap fits around the portion of the disk *5* that extends out of the casing. On the lower end of the bolt *9* is a nut *12* for retaining the cap *11* in place, and co-operating 85 with the nut *12* is another nut *v* to form a binding post to which the ground wire *14* of the condenser *l* is connected. Surrounding the portion *10* of the cap *11* is a resistance *B* which has one end connection by a 90 wire *16* to the binding post *t*, and the other end connected by a wire *17* with a source of current such as a battery which is in turn connected with ground.

In the upper end of the casing *a* is a 100 chambered metallic body or holder *i* which contains a condenser *l*, the terminal *22* of which is connected with the bottom or inner plate *n* of the condenser holder, while the other terminal *24* is connected with a 105 wire *25* leading from the interrupter contact *f*. The bottom plate *n* of the condenser holder has a socket *m* for receiving the

upper end of the coil core σ . On the top of the holder i and insulated therefrom is a fixed contact 28 to which the upper terminal of the primary winding is connected by 5 a wire 29, and coöperating with this contact is a spring contact k which is fastened to the post 31, also on top of the holder. For permitting the contacts 28 and k to be engaged and disengaged, when it is desired 10 to use or cut out the same, the cap c is rotatably mounted on the ring d , being connected thereto by a bayonet joint. Fastened to the cap c is an operating handle b and a screw h passing through the cap is adapted 15 to engage a stop 36 on the condenser holder 20 so as to limit the movement of the cap when the insulating projection g causes the contact k to engage the contact 28. A make and break device D is used in connection 20 with the contacts 28 and 30 for the starting by the battery or primary current.

From the foregoing it will be understood 25 that current is brought from a battery by the wires 17 and that one pole of said battery or other source of current is grounded. The wire 17 is connected to a ring 40 from which the current passes to the resistance, coil B into the ring 41. The ring 41 is connected by a wire 16 to the binding post t 30 which forms one terminal of both the primary and secondary coils A and C , respectively. From the binding post t the current passes through the primary coils A to the conductor 29 which leads to the post 28. From the post 28 current passes into the 35 switch arm h whenever the cap c is in such position that the insulated member g holds the member in contact with the post 28. From the member h the primary current or 40 battery current passes into the conductor 38 which connects with the interrupter D . Now the interrupter D comprises a pivoted arm e which is operated in one direction by a spring so that it will contact with the 45 contact f , and I provide a revoluble member e' which is provided with suitable projections on its surface adapted to throw the member e away from the contact f and against the insulated stop f' so as to break 50 the primary circuit, the member e being swung back into contact with the post or contact f so as to close the primary circuit by the spring before mentioned, as soon as the projection of the member e' which lifted

55 the member e has passed from beneath the member e' . Leaving the contact f , the primary current flows through the conductor 25 to ground and thence to the negative side of the battery, or other source of current. It will be seen, moreover, that the 60 condenser l is connected across the interrupter D , there being a conductor 24 connected to the conductor 25 and to one side of said condenser, while the other side of said conductor is connected to the post 22 from

which point electrical connection is made through the disk n , core c , bolt u , contact v and conductor 14 to ground. The secondary circuit leads from the binding post t through the secondary coil D , thence to the binding post r and thence to the conductor 42 which leads to the distributor and spark plug, one side of which latter element is always grounded. From the grounded side of the spark plug the secondary circuit is completed through the battery and coil D to the post t , and also through the interrupter D and a primary coil A to the same point whenever the member e is in contact with f . It will be understood further that I prefer 70 to drive the revoluble member e' of the interrupter D from the engine by means of a gear mechanism which will permit me to rotate said member e' by hand when the engine is stopped. This is for the purpose of 75 obtaining a spark from the previously described apparatus when the engine is stopped in order to ignite a charge of gas which may be held in one of the engine cylinders and thus start the engine without 80 cranking. However, it will be understood 85 that such gear mechanism is well known in the art of ignition, having been commonly used for driving magneto generators, and consequently I do not deem it necessary to 90 describe such mechanism in the present application and do not lay claim to the same in combination with any other features of 95 the device shown and described herein.

By suitably proportioning the relation of 100 the primary winding A to the external resistance B , it is possible to hold the inductive action of the spark coil approximately 105 constant both at the lowest and highest speeds of the motor. As a result, the ignition spark will be of approximately uniform strength. At low motor speed and a correspondingly slow break in the primary circuit, the ohmic resistance of the coil B reduces the current flow through the primary 110 winding to a predetermined maximum. On the contrary, in case of a higher motor speed with corresponding quicker breaks in the primary circuit, the current is reduced 115 owing to increased impedance of the coil this reducing the ohmic drop in the external resistance and leaving a higher voltage available for the primary winding of the coil.

From the foregoing description, taken in 120 connection with the accompanying drawings, the advantages of the construction and the method of operation will be readily apparent to those skilled in the art to which the invention appertains, and while I have 125 described the principle of operation of the invention, together with the apparatus which I now consider to be the best embodiment thereof, I desire to have it understood that the apparatus shown is merely 130

illustrative, and that such changes may be made when desired as are within the scope of the claims appended hereto.

Having thus described the invention, what

5 I claim as new is:—

1. A device of the class described comprising a casing, a core therein, primary and secondary windings surrounding the core, a cap for the end of the casing, said cap having a spool-like projection of non-magnetic material, and a resistance coil on the projection and connected with the primary winding.

2. A device of the class described comprising in combination, a casing, a plate of insulating material therein, binding posts on the plate, a core within the casing, primary and secondary windings on the core and connected with the binding posts, a cap attached to the casing and covering the binding posts and having a projecting portion, a resistance coil on the said projecting portion and connected by one of the binding posts in series with the primary winding, a connection between the primary winding and core, and a binding post connected with the core and extending through the said projecting portion of the cap.

3. A device of the class described comprising a casing, a condenser holder in one end of the casing, an insulating plate in the other end, a core between the plate and holder, primary and secondary windings on the core, binding posts in the said plate for connection with the terminals of the secondary winding, one terminal of the primary winding being connected with one post, a resistance coil connected with the binding post to which the primary winding is connected, 40 the other terminal of the primary winding being connected with the condenser holder, a make and break device connected with the primary winding, and a condenser in said

condenser holder in shunt relation to the make and break device.

45

4. A device of the class described comprising a casing, a metallic body disposed in one end of the casing, a plate of insulation in the other end of the casing, binding posts in the said plate, a magnetic core in contact with said body, a primary winding on said core having one end connected with one binding post and the other end connected to a switch on the said metallic body, a secondary winding having its terminals 55 connected with the binding posts, a cap applied to the lower end of the casing and having a spool-like portion, a bolt extending through the said spool-like portion of the cap and anchored in the said plate in 60 electrical connection with the core, said bolt forming a binding post, and a resistance coil on the projecting portion of the cap and connection with the binding post to which the primary winding is connected.

65

5. A device of the class described comprising a casing, a metallic condenser holder in one end thereof, a core connected with the said holder, a primary winding connected with the said holder, a secondary winding, a 70 resistance coil connected with the primary winding, means connected with the end of the core opposite from the condenser holder in the primary circuit, a make and break device connected with the primary winding, 75 switch means for connecting the make and break device in series with the winding, and a condenser in the said holder disposed in shunt relation to the make and break device.

In testimony whereof, I affix my signature 80 in the presence of two witnesses.

ERNST EISEMANN.
